UNITED STATES PATENT OFFICE.

JOHN R. ELBERG, OF KANSAS CITY, MISSOURI.

CURTAIN DOOR EXTENSION.

1,162,990.

Specification of Letters Patent.

Patented Dec. 7, 1915.

Application filed November 24, 1913. Serial No. 802,673.

To all whom it may concern:

Be it known that I, JOHN R. ELBERG, a citizen of the United States, residing at Kansas City, in the county of Jackson and 5 State of Missouri, have invented certain new and useful Improvements in Curtain Door Extensions, of which the following is a full, clear, and exact description, such as will enable others skilled in the art to 10 which it appertains to make and use the same.

The invention relates to removable curtain door extensions for automobiles, where- 15 in the curtain is so connected to the usual body door that it swings with the door, dis- pensing with the manipulation of the curtain to open or close the door.

The present invention seeks to provide an 20 improved attachable and detachable post ex- tending upward from the usual body door so that the side curtain may be attached to the post and form an extension of the door, converting the usual low body door to the 25 full height door, the invention being an im- provement on that of the applicant's former application Serial Number 797,995.

In the invention of the former applica- 30 tion two connections are required on the body door and the frame has two legs one 35 of which lies across the window lights of the curtain obstructing the view; while in the present invention there is but one connection on the body door, and the frame consists of a single upright post which does 40 not obstruct the view.

The fact that the single post is made at 45 less expense, and can be forwarded from the factory in lengths long enough for any automobile in use, and cut to fit by the assembler, 50 is also very advantageous. It was found necessary in marketing the former frame, to make the frame to fit the automobile and no stock could be provided without carrying various sizes; while with the single 55 post of the present invention, but one size is required, which reduces the expense and simplifies the problem of carrying a stock.

With these and other objects in view, the 60 invention consists in the features of con- struction, combinations and arrangements 65 of parts hereinafter set forth, illustrated in the accompanying drawings and more par- ticularly pointed out in the appended claim.

In the drawings:—Figure 1 is a view in 65 elevation of the improved door extension applied to an automobile. Fig. 2 is a view

in elevation of the door extension. Fig. 3 is a view in elevation of the door extension post. Fig. 4 is a view of one end of the door extension post. Fig. 5 is a view in 60 elevation of the connection which is secured to the body door to receive the post. Fig. 6 is a view of one end of the connection. Fig. 7 is a view of the pad which is provided to prevent the post from cutting the curtain. 65 Fig. 8 is a view of one end of the pad.

The body 1, top 2, curtains 3 and 4, and door 5 which is hinged to the body by hinge 6, are all of well known construction.

To the inner side of, and near the swing- 70 ing edge of the door 5 is secured the dove- tailed connection 7 by screws 8 passing through holes 9 of the connection and being embedded in the door. The connection 7 has dove tailed inner sides 10 which are 75 tapered lengthwise as regards distance be- tween, and the post 11 is provided with an enlarged end having tapering dovetail shaped sides 12 to fit the connection, so that when the post is placed in the connection it will 80 stand rigid in every direction but may easily be lifted therefrom.

When the top and curtains 3—4 are 85 lowered or removed from the body 1 the only evidence of the door extension is the con- nection 7 which is allowed to remain secured to the door 5, but when the top 2 and curtains 3—4 are raised as illustrated the post 11 is placed in the connection 7, the pad 13 is placed over the upper end of the post and 90 the curtain 3 connected thereto by placing the pocket member 14 over the pad and the post. The pocket member 14 is sewed or otherwise secured to the corner of the cur- tain 3 and when in place lies inside the post 95 11, while the curtain lies outside the post. The pad 13 is formed by folding a piece of leather or like material so the end 15 is closed, and stitching therein the seams 16 forming a pocket open at 17. 100

Post 11 is forwarded from the factory in the longest lengths required so that the assembler may cut the upper end to the length desired and place the pad 13 thereon, this obviates the necessity as heretofore of carrying more than one length of extension frame in stock at the assembling stations. 105

The pocket member 14 may be secured to any side curtain, this however is included in the former application and claimed here- 110 in only in connection with the improved ex- tension frame.

What I claim is:—

In a curtain extension for vehicle doors, the combination with the door of a vehicle, of a connection secured to the door, a post detachably resting in said connection, a curtain, a pad resting over and around the upper end of said post but not secured or attached thereto, and a pocket secured to the inner side of said curtain, said curtain positioned outside of said post and said

pocket positioned inside of said post with the post resting in said pocket and supporting said curtain without securing or attaching said curtain to said post.

In testimony whereof I affix my signature in the presence of two witnesses.

JOHN R. ELBERG.
